UNITED STATES PATENT OFFICE.

GEORGE MOLIDOR, OF INDEPENDENCE, KANSAS.

DESIGN FOR A CAN-OPENER.

SPECIFICATION forming part of Design No. 27,532, dated August 17, 1897.

Application filed June 24, 1897. Serial No. 642,200. Term of patent 7 years.

To all whom it may concern:

Be it known that I, GEORGE MOLIDOR, a citizen of the United States, residing at Independence, in the county of Montgomery and 5 State of Kansas, have invented and produced a certain new and original Design for Can-Openers; and I do declare the following to be a full, clear, and exact description of the invention, such as will enable others skilled in 10 the art to which it appertains to make and use the same.

My invention relates to a design for a can-opener.

It relates to the entire configuration of the 15 can-opener.

My invention relates particularly to the design for a can-opener, as illustrated in the accompanying drawing, in which the figure is a perspective view of a can-opener embodying my design.

The leading features of my design appear in the following description.

1 represents the globular handle, and 2 the shank connecting said handle by an annular angular shoulder 3.

The shank 2 comprises the cylindrical base-section 4, formed with the parallel walls 5,

and the shank itself tapers gradually, while still preserving its cylindrical contour, from the base-section 4 to the shoulder 3.

A series of diamond-pointed teeth 6 extend annularly about seven-eighths of the distance around the base-section, and they project longitudinally from the base-section, as shown, and are of uniform length, breadth, and thickness, as shown.

A portion 7 of the base-section 4 is left blank, as shown.

The teeth are each provided with beveled edges on each end, which extend from the 40 point 8 to the heel 9.

Having thus fully described my invention, what I claim as new and useful, and desire to secure by Design Letters Patent of the United States, is—

The design for a can-opener, substantially as herein shown and described.

In testimony whereof I hereunto affix my signature in presence of two witnesses.

GEORGE MOLIDOR.
